INTERCOMMUNICATION SYSTEM

Robert Helmert, Berlin, Germany, assignor to
 C. Lorenz Aktiengesellschaft, Berlin-Tempel-
 hof, Germany, a company

Application July 29, 1939, Serial No. 287,198
 In Germany August 3, 1938

4 Claims. (Cl. 179—4)

This invention relates to intercommunication systems, and more particularly to signaling arrangements in telephone systems in which supervisory signals, such as call signals, disconnect

5 signals and the like, are transmitted by alternating currents of different audio frequencies.

It is a known expedient to effect supervisory signal transmission over telephone lines by alternately transmitting two different frequencies in a close succession and to cause the receiving apparatus to respond only in cases when these signals arrive in a predetermined manner so as to avoid that the supervisory signal equipment be released by speech currents.

10 15 In one specific aspect of my invention, the receiving equipment of a telephone or other intercommunication system is so arranged that the armature of the receiving relay in either of its two positions operates an auxiliary relay, and 20 these two auxiliary relays are arranged to control a further auxiliary relay which is slow to operate.

According to a further object of this invention, 25 the further auxiliary relay is caused to release when the two first-mentioned relays are continually operated, means being provided to maintain each one of said two relays operated during the intervals in which the armature of the receiving relay establishes an operating circuit for 30 the other of said two auxiliary relays.

In accordance with still a further feature of 35 this invention the release time of the two first-mentioned auxiliary relays is determined by a condenser connected across the junction point of the said relays with their respective contact of the armature of the receiving relay in such manner that the charge currents from this condenser involves an additional excitation of the two auxiliary relays mentioned.

40 According to a further aspect of my invention, the velocity with which the two frequencies constituting a supervisory signal are alternately impressed upon the line corresponds to the highest speed of response of the receiving relay of the signal receiving apparatus. It is thus possible to so time the further auxiliary relay that 45 it will release and thus cause the indication of a supervisory signal only when the frequencies incoming from a signal transmitting apparatus are intermittently transmitted with a given speed of alteration, since at a higher speed of alteration the relay is incapable of following this higher speed so that one only of the two first-mentioned relays is caused to attract, while 50 at a lower speed of alteration between the in-

coming frequencies of different kind the relays just mentioned are caused to release when the contact or armature of the receiving relay is set to the opposite side.

It is still a further object of this invention to 5 provide means for transmitting two different supervisory signals and to so arrange the receiving apparatus that the armature of the receiving relay at the end of incoming signals remains in a given one of its two end positions in order to 10 selectively control a given one of two different supervisory signals in response to the position in which the armature is set. The final position of the armature at the end of the incoming train of different signal frequencies is predetermined 15 by causing one of these frequencies to persist for a predetermined interval of time at the end of the alternating signal train.

20 My invention will be more fully understood from the following description taken in conjunction with the accompanying drawing, which diagrammatically shows one embodiment of my invention.

25 Referring to the drawing, the operation of the system is performed as follows: When the subscriber at the standard central battery telephone apparatus T removes his handset, the double wound relay J is caused to operate by current through both the windings I and II in series with apparatus T. The relay R which in a condition of rest is energized over the winding II of relay S and the back-contact $i2$ becomes de-energized, so that after some delay this relay will shift its contact $r1$ and $r2$ to the released portion shown in the drawing. Before this occurs, however, the winding I of relay S receives an alternating current of say 50 cycles from the generator G3 over the contact $r1$ and the contact $i2$. The contact s of relay S is thus caused to vibrate in rhythm with the frequency of the generator G3 so as to alternately switch the 30 audio frequency generators G1 and G2 in circuit. The different frequencies from these two audio frequency generators are transmitted over transformer T_{r1} , the line $a2b2$ and the transformer T_{r2} to the tuned amplifiers and rectifiers F1 and F2 so that the two windings of the receiving relay E are intermittently energized with the result that the armature e oscillates so as to alternately energize the relays A and B. The condenser C3 shunted across the two contacts between which the armature e of the receiving relay E vibrates is so dimensioned that the charge current at 50 cycles is sufficient to maintain the 35 relays A or B energized during the short inter- 40

val of time at which the armature e is connected to the other of the said relays. When the two relays A and B are simultaneously energized, a relay H is short-circuited by the contacts $a2$ and $b2$ of the relays A and B, respectively. The relay H reverts its contacts so that the relay D is energized over the contact $h3$.

When the relay R of the transmitting side releases after some delay, the winding I of the relay S is so energized by the direct current flow through the relay Z that the contact s of relay S remains in the position shown in the drawing, thus maintaining the audio frequency generator G1 connected in circuit. Thus, the relay A in the receiving position remains energized due to the energization of the upper winding of the receiving relay E, while the relay B is caused to deenergize. The short-circuit across the relay H is thus removed by the opened contact $b2$ so that relay H is again operated to revert its contact. Now, an energizing circuit is established for the relays G and N through both windings I and II of double wound relay N in series with the winding of relay A. The relay N reverts its contact n , whereupon the call indicating lamp AL is lighted. This indicating lamp may be extinguished by inserting the plug St into the jack Kl. The energizing circuit for the relays N and G remains established over the contact g after the release 30 of the relay D.

The disconnection of the generator G1 and the switching-through of the speech line at the transmitting position is effected by the slow-to-operate relay Z.

35 The speech currents cannot cause the relay H of the receiving apparatus to release since it must be considered impossible that the two frequencies to which the devices F1 and F2 are tuned will alternately arrive at a frequency of 50 cycles during a time which will suffice to simultaneously energize the two relays A and B and thus to cause the release of the relay H.

When the subscriber at the telephone station T again restores the handset, the relay J releases. The contacts of this relay are restored to normal so that the winding II of the relay S now receives an alternating current of 50 cycles from the generator G3. The devices F1 and F2 of the receiving apparatus are thus alternately rendered effective in response to the alternate effectiveness 50 of the audio frequency generators G1 and G2 of the transmitting station when the contact s of relay S oscillates in rhythm with the 50-cycle alternating current from generator G3. The movement of the armature e of the receiving relay E causes the two relays A and B to operate so that their contacts $a2$ and $b2$, respectively, establish a short-circuit across the relay H which latter releases so as to revert its contacts. The relay D is therefore energized over the contact $h3$. When the relay Z of the transmitting apparatus releases after some delay, the winding II of relay S is so energized over the winding of relay R that the contact s remains in a position in which the audio frequency generator G2 is connected in circuit with the result that the relay A of the receiving apparatus releases while the corresponding relay B remains attracted. The short-circuit across the relay H is thus removed 60 so that this relay operates whereupon the energizing circuit for the relays G and N is interrupted, while the relay D still remains operated.

The relay N releases so that the indicating lamp SL announcing the disconnect signal is lighted. This indicating lamp may be extinguished by removing the plug St from the jack Kl. In the transmitting station, the audio frequency generator G2 is disconnected as soon as the slow operating relay R has operated.

My invention is by no means restricted to the embodiment heretofore illustrated and described by way of an example. It is likewise possible 10 to influence the relay E of the receiving apparatus over a transmission line over which telegraph signals are also transmitted. The single difference between the telegraph signal and the signal which is intended to control the action of the relay H 15 is that the frequency transmitted by the generator G3 of the transmitting station is higher than the maximum speed of telegraph signal transmission. The condenser C3 and the relays A and B are so dimensioned that the relays A and 20 B release during the interruptions or spaces between two signals and during signal, respectively. It is also possible to cause the generator G3 of the transmitting apparatus to transmit a frequency which corresponds to the speed of telegraphic signals provided that the telegraph transmission is so arranged that at given time intervals, e. g. at the end of each character a longer pause is inserted between the telegraph signals and provided that the release time of the relay 25 H is so dimensioned that it is longer than the total time of a signal transmitted between two such pauses.

What is claimed is:

1. In an electric communication system, supervisory signal receiving equipment which is adapted to indicate supervisory signals composed of alternating currents of different frequencies transmitted with a given relation to each other and which comprises a polarized receiving relay 40 adapted to move its armature in response to alternating currents of different frequencies constituting the said supervisory signals, two auxiliary relays adapted to be alternately energized in response to the instantaneous position of the said armature, and a third auxiliary relay for releasing supervisory signals in response to the simultaneous energization of the said two auxiliary relays.

2. In an electric communication system as defined in claim 1, in which means are provided to effect two different supervisory signal indications, each dependent upon the final position of the said armature at the end of incoming signaling currents.

3. In an electric communication system as defined in claim 1, in which means are provided to indicate a supervisory call signal when the said armature remains in one end position at the conclusion of incoming signal currents, and to indicate a disconnect supervisory signal when the said armature remains in its opposite position at the end of incoming supervisory signaling currents.

4. In an electric communication system according to claim 1, in which means are provided which in response to the correct incoming frequency maintain the one of the said auxiliary relays operated during the interval of time during which the said armature is connected to the other of the said two relays.

ROBERT HELMERT.
